UNITED STATES PATENT OFFICE.

RAY H. HANKS, OF HENRYETTA, OKLAHOMA.

POTATO DIGGER.

Application filed August 19, 1920. Serial No. 404,508.

To all whom it may concern:

Be it known that I, RAY H. HANKS, a citizen of the United States, residing at Henryetta, in the county of Okmulgee and 5 State of Oklahoma, have invented certain new and useful Improvements in Potato Diggers; and I do hereby declare the following to be a full, clear, and exact description of the invention, such as will enable others 10 skilled in the art to which it appertains to make and use the same.

This invention relates to certain new and useful improvements in a potato digger and has for its primary object the provision of 15 an improved form of potato digger which will effectively separate the potatoes from the dirt as the former are raised to position upon an elevator.

The invention has for another object the 20 provision of a potato digger of the above stated character in which the operative parts will be mounted in a simple form of frame and the potato digging and raising elements readily adjusted for efficient operation of 25 the machine.

The invention has for another object, the provision of a potato digger which is composed of the minimum number of operative parts and arranged in such a manner that all 30 of the parts may cooperate to the highest extent, all of the operative parts being driven from the forward axle or main axles of the machine.

The invention has for a still further object, 35 the provision of a potato digger of the above stated character in which the plow or digging member together with the small colters and the forward end of the potato raising or gathering member may be readily adjusted vertically as may be desired.

With the foregoing and other objects in view as will appear as the description proceeds, the invention consists in the novel construction, combination and arrangement of 45 cooperating elements as hereinafter more specifically set forth, claimed and shown in the accompanying drawings in which—

Figure 1 is a top plan view of the machine with the parts in operative position.

Figure 2 is a side elevation thereof.

Figure 3 is a front elevation with parts broken away.

Figure 4 is an enlarged vertical section through the forward portion of the machine.

Figure 5 is a fragmentary plan view of the driving connection between the gathering mechanism and the conveyor.

Referring more in detail to the drawings, in which similar reference characters designate corresponding parts throughout the several views, 1 designates the rotatable shaft on which the ground wheels 2 are rigidly mounted so that the shaft 1 serves as the axle of the machine. A main longitudinal frame 3 is mounted at the forward portion 60 on the axle shaft 1 and has the rear ground wheels 4 positioned beneath the rear end portion, the wheels 4 being mounted in a suitable manner on the pivot shafts 5 having the 65 upwardly and forwardly directed supports 6 which are swiveled in a suitable manner in the rear portion of the side members of the main frame 3 so that the machine may be readily turned to either side. A suitable 70 draft tongue 7 is connected at its rear end with the connecting links 8 which are extended in diverging directions and pivotally connected to the forward corners of the main frame 3, as shown at 9. The suitable double 75 tree 10 or the like is carried by the draft tongue 7, as shown at 11 and has single trees 12 mounted thereon so that four or more 80 draft animals may be harnessed to the machine. This machine is shown as being constructed to be drawn by four draft animals 85 but any other suitable number may be employed.

The axle shaft 1 has the driving gear 90 wheel 13 mounted thereon at one side of the main frame 3 and adapted for rotation with the axle shaft 1. The seat 14 is mounted on the frame 3 above the axle shaft 1 and preferably over one side of the frame, as shown 95 in the drawings.

An upper transverse shaft 19 for the endless potato gathering member, which is designated in general by the numeral 20, is mounted in the main frame 3 and extended transversely thereof, said shaft 19 having a 100 gear 21 on one end meshing with the drive gear 13 of the axle shaft 1. The lower shaft 22 of the potato gatherer 20 is mounted for rotation in a pair of pivoted suspending bracket members 23, which have their upper 105 ends pivoted to the forward portion of the main frame 3, forwardly of the axle shaft 1. A pair of small colter wheels or discs 24 co-operate with the plow point or digger 25 and are journaled on a transverse member 110

or cross bar 26 carried by the lower portion of the bracket arms 23 so that as the plow point or digger 25 passes under the potatoes to raise or dig the same, the colter wheels or 5 discs 24 will break up the dirt at each side of the wheel and make it much easier for the potato gatherer 20 to gather up the potatoes, as will be later clearly understood. Digger 25 is journaled on an offset or deflected portion of bar 26 as shown. A jointed raising bar 27 is connected at one end to the digger 25 while its opposite end is rigidly connected with a short shaft 28 which has the raising and lowering lever 29 connected with one 15 end and carried on the rack 30 of conventional form. The rack 30 is provided for cooperation with the spring latch to lock the lever 29 in position. It will therefore be seen that by adjusting the lever 29 the lower 20 end of the potato gatherer 20 as well as the plow point or digger 25 and the colter member 24 may be readily raised or lowered and placed in proper position for effective operation of the machine.

25 While the complete construction and operation of this machine may be readily apparent, it may be stated that after proper adjustment of the lever 29 to place the plow point or digger 25 and colter members 24 at 30 the proper elevation, the machine may be driven along a row of potato hills and owing to the operative parts being controlled by rotation of the axle shaft 1, the potatoes ex-

cavated or thrown up from the ground will be caught by the potato gatherer 20 and elevated, the greater portion of the dirt dropping through the potato gatherer 20.

35 While the preferred embodiment of the invention has been shown and described it will be understood that minor changes in the 40 details of construction, combination and arrangement of parts may be resorted to within the scope of what is claimed without departing from the spirit of the invention.

45 What is claimed is:

1. A machine of the class described having a movable cross bar, a digger member adjustable through movement of the cross bar, colters on said cross bar cooperating with the digger member, and means to adjust the 50 digger member to different heights and on said cross bar.

2. A machine of the class described having brackets, a digger member, a cross bar, said digger member resting against the cross 55 bar, said cross bar having a deflected portion to vary the position of the digger member through its movement, a conveyor associated with the digger member, and means to drive said conveyor on said cross bar. 60

In testimony whereof I affix my signature in presence of two witnesses.

RAY H. HANKS.
